(57) **CLAIM**

The ornamental design for a nonwoven fabric, as shown and described.

DESCRIPTION

FIG. 1 is a perspective view of a nonwoven fabric, embodying the new design;

FIG. 2 is a top plan view thereof;

FIG. 3 is a rear plan view thereof; and,

FIG. 4 is a cross sectional view taken along line 4-4 of FIG. 2 showing a profile of the new design at the point of the cross section and not what lies beyond it.

The broken lines along the border in the drawings depict the boundaries of the claimed design and form no part of the claimed design. The broken lines in the drawings depict portions of the article that form no part of the claimed design.
